UNITED STATES PATENT OFFICE

2,141,986

JOINT AND DOWEL STRUCTURE FOR
ROADWAYS

Louis B. Johnson, Baltimore, Md.

Application January 25, 1938, Serial No. 186,881

3 Claims. (Cl. 94—18)

The present invention relates to a combined joint and load-transfer assembly for use in roadways, pavements, and the like, and more particularly to such an assembly in concrete roadways 8 constituting a positive contraction joint and load-transfer device.

One of the objects of the invention is the construction of a joint having a dowel assembly associated therewith for use in a concrete roadway 10 or the like, said assembly serving to hold the joint normal to the sub-grade of the roadway with the dowels parallel to each other and likewise parallel to the finished grade.

Another purpose of the invention is the building- 15 of a unitary dowel assembly and contraction joint for use in a concrete roadway, the unitary device having means for anchoring and properly positioning the joint and assembly in the roadway.

20 Still another aim is the formation of a unique joint for use in concrete pavements and the like.

The invention of the instant application is an improvement on the load-transfer device shown 25 in my prior Patent No. 2,104,866, issued January 11, 1938.

Other aims and objects will be apparent to those skilled in the art from the description of the invention hereinafter appearing, when read in conjunction with the appended drawing forming 30 a part hereof, and to which reference is now made and in which:

Fig. 1 is a plan view of the novel combined joint and dowel assembly prior to its insertion in a concrete pavement or roadway, and showing the 35 relative position of the anchoring means.

Fig. 2 is a front elevational view of the device shown in Fig. 1.

Fig. 3 is a view partly in section and partly in elevation showing the manner of mounting the 40 combined joint and dowel assembly in a concrete roadway, and.

Fig. 4 is a plan view of one of the anchoring means or brace rods.

In my prior Patent No. 2,104,866, referred to 45 above, there is disclosed a load-transfer device for roadways to be used in conjunction with an expansion joint or expansion material. The joint or material forms no integral part of the device disclosed in the aforementioned patent. The instant invention, on the other hand, contemplates a novel joint forming an integral part of the device and comprises a metal plate welded to the top of the dowels and in line with the upright or vertical portion of the angle iron resting in the 50 sub-grade of the roadway forming a supporting

member. This arrangement constitutes a load-transfer device and, in addition thereto, a positive contraction joint. Means are provided for permanently anchoring the device in the roadway prior to the pouring of the concrete.

Referring now to the drawing the reference character A designates the combined joint and dowel assembly which comprises an elongated supporting member 10 in the form of an angle iron, said angle iron having a horizontal portion 10 11 and a vertical portion 12 at right angles thereto.

A series of similar dowel pins or bars are designated by the reference numeral 13, each pin or bar being characterized by a horizontal section 14 and a downwardly extending curved section 15, the latter projecting from said horizontal section 14 and being secured, as by welding or the like, to the horizontal and vertical portions 11 and 12 of the supporting member 10. By reference to Figs. 1 and 2 of the drawing it will be noted that the downwardly curved portion 15 of each dowel is positioned in a plane angularly disposed with respect to the horizontal and vertical portions 11 and 12 of the supporting member 10. 20 Also it will be noted that the dowels on the left hand side of the device A are oppositely positioned with respect to the dowels on the right hand side of the device, this is to say, in intersecting planes. Secured to the horizontal portion 14 of each dowel, as by welding or the like, and in alignment with the vertical portion 12 of the supporting member 10, is a metal plate forming a joint J. A plurality of washers 17 25 are welded or otherwise secured, in spaced relation, to the horizontal portion 11 of the supporting member 10 adjacent the free edge thereof and extending therebeyond and a plurality of similar washers 18, in vertical alignment with the washers 17, are secured, also by welding or 30 the like, to the horizontal portion 14 of a plurality of dowels 13 to one side thereof and forwardly of the joint J. By reference to Fig. 3 of the drawing it will be noted that the sub-grade 35 of the road is designated by the reference character G and the concrete which hardens into slabs by the reference character C. In assembling the device for use the combined joint and assembly A is positioned on the sub-grade G of the roadway with the joint J normal thereto. A plurality of pins 19 are then inserted through the aligned 40 washers 17 and 18 and driven into sub-grade G to position the device on the surface of the latter. The pins 19 adjacent the opposed ends of angle iron 10 have associated therewith anchoring rods 50

55

or braces 20. Each of the latter is equipped with end washers 21 and 22 welded or otherwise secured to the ends thereof. The ends of pins 19 pass through the washer 21 while the other washer 22 receives an anchoring pin 23, the latter being driven into the sub-grade G of the roadway. When the concrete C is poured it will entirely enclose the combined joint and dowel assembly A, and the concrete is built up to form the roadway, the surface of which is designated by the reference numeral 25.

When the concrete has been poured on both sides of the joint J a plane of weakness is set up by the vertical leg 12 of the supporting member 10 and the metal plate forming the joint J welded to the top of the dowel members 13. The concrete as it hardens shrinks and cracks between the upright leg 12 of the supporting or angle member 10 and the metal joint J forming an irregular crack 26. This crack provides, through friction, additional load transfer value.

From the above description it will be apparent that the entire assembly A is held in place by the brace rods 20 and the locking pins 19 and 23. The locking pins and brace rods hold the unit in its desired true position and in which position it is adapted to withstand the working loads imposed thereon during the laying of the roadway. The brace rods resist the disturbing forces exerted by the finishing machine and hold the dowel bars and contraction plate in their correct position at all times. The brace rods and anchoring pins, as will be understood, remain in the concrete C and provide reinforcement for the dowel and joint assembly, the latter being very effective in providing an efficient joint of great load transfer value, as well as of great strength and rigidity.

Obviously the invention is susceptible to more or less modification than what has been shown and described, and desirable changes may suggest themselves to those skilled in the art without departing from the spirit of the invention. It is contemplated to cover all such modifications and to be limited in this respect only as may be necessary by the scope of the claims hereto appended.

What I claim is:—

1. A paving construction unit comprising a supporting member having a vertical portion, a plurality of dowels positioned at spaced intervals extending above said member and transversely thereof, said dowels each having an extension rigidly connected to said member, and a contraction member secured to said dowels in alignment with and spaced from said vertical portion.

2. A paving construction unit comprising a supporting member having a vertical portion, a plurality of dowels positioned at spaced intervals transversely above said member, each dowel having means securing same to the latter, a plate secured to the upper surface of the dowels in vertical alignment with said portion, means secured to said dowels and supporting member for anchoring the unit, said means comprising aligned washers, pins passing through said washers, and brace rods adjacent the opposed ends of said supporting member.

3. A combined load transfer and joint assembly comprising an angle supporting member having a vertical portion, a plurality of spaced dowels secured to and extending transversely above said member, and a contraction plate rigidly mounted on the upper surface of said dowels in alignment with said vertical portion.

LOUIS B. JOHNSON.
